DESIGN FOR AN ARMCHAIR FRAME

Louis Vavrik, Toledo, Ohio, assignor to The Hettrick Manufacturing Company, Toledo, Ohio, a corporation of Ohio

Application August 28, 1936, Serial No. 64,604

Term of patent 14 years

To all whom it may concern:

Be it known that I, Louis Vavrik, a citizen of the United States and resident of Toledo, Lucas County, Ohio, have invented a new, original, and ornamental Design for an Armchair Frame, of which the following is a specification, reference being had to the accompanying drawing, forming a part thereof.

In the drawing:

Figure 1 is a front perspective view of the armchair frame showing my new design; and

Figure 2 is a rear perspective view of the armchair frame shown in Figure 1.

I claim:

The ornamental design for an armchair frame as shown.

LOUIS VAVRIK.
